A. Romadka

UNITED STATES PATENT OFFICE.

ANTHONY ROMADKA, OF MILWAUKEE, WISCONSIN, ASSIGNOR TO ROMADKA BROTHERS, OF SAME PLACE.

IMPROVEMENT IN TRUNK HINGES AND STAYS.

Specification forming part of Letters Patent No. 158,317, dated December 29, 1874; application filed October 5, 1874.

To all whom it may concern:

Be it known that I, A. ROMADKA, of the city of Milwaukee and State of Wisconsin, have invented certain new and useful Improvements in Combined Cast Hinges and Clamps for Trunks; and I do hereby declare that the following is a full, clear, and exact description of the same, reference being had to the accompanying drawings, in which similar letters indicate like parts, and where—

Figure 1 is a perspective view of my device upon a trunk opened, showing its operation; Fig. 2, a side view of the same on a trunk closed; and Fig. 3, a rear view of the parts of my device separate from the trunk.

The object of my invention is to produce a self-supporting hinge and clamp combined for trunks that shall consist of only two parts, so constructed that, when applied, they will serve as clamps and supporting-hinges for the lid or cover when thrown back, and also will serve to prevent any lateral motion of the parts of the trunk when closed. Another special object is to so construct the parts that the strain will come upon the strengthened parts of the clamps when the top of the trunk is thrown back. It consists in casting the upper clamp with a strengthening-bulb and a re-entering pin, all in one piece; also, in casting the lower clamp with a similar strengthening-bulb, a flange on the rear side, and socketed bulb for receiving the pin on the upper clamp, in one piece.

In the drawings, D and C are the two parts or clamps thus constructed. The upper part, C, is cast in the form of a corner clamp with a strengthening-bulb, F, as shown in all the figures, and with a re-entering pin, a, as shown in Fig. 3. The lower part, D, is cast in like form, with strengthening-bulb G, flange E,

lip b, and socketed bulb c, for receiving the re-entering pin a, as shown in the same figure. Thus constructed they are applied and attached to the parts of a trunk, as shown in Figs. 1 and 2, in which it will be seen they clamp the corners and serve as hinges.

When the lid or top of the trunk is thrown back the swell upon the upper clamp bears upon the flange upon the lower, but in such a way as to bring the principal strain at the corners, at the same time supporting the cover, as shown in Fig. 1.

When the lid or cover is closed the lip b enters inside of the upper clamp, and thus, in combination with the outer end of the socket c, and the inner shoulder of the re-entering pin, prevents any lateral movement of the parts.

It is obvious that the parts may be cast of any size and of any suitable material, and that their inner surface may be cast to conform to the outer surface of the trunk, as shown at e, Fig. 1, and thus be made to bear upon any desired portion.

Having thus described my invention, what I claim is—

1. The combination of the clamp C, cast with a strengthening-bulb and the re-entering pin, and the clamp D, cast with a similar bulb, a supporting-flange, and socketed bulb, substantially as and for the purpose set forth.

2. In a combined clamp-hinge for trunks, the re-entering pin a and socketed bulb c, when cast with the parts of the same, as and for the purpose set forth.

A. ROMADKA.
